United States Patent Office.

P. A. LA FRANCE, OF ELMIRA, ASSIGNOR TO HIMSELF AND H. R. KENDALL, OF NEW YORK, N. Y.

Letters Patent No. 70,865, dated November 12, 1867.

IMPROVEMENT IN COMPOSITOR'S COPY-HOLDER.

The Schedule referred to in these Letters Patent and making part of the same.

TO ALL WHOM IT MAY CONCERN:

Be it known that I, P. A. LA FRANCE, of Elmira, Chemung county, New York, have invented a new and improved Compositor's Copy-Holder; and I do hereby declare that the following is a full, clear, and exact description thereof, which will enable others skilled in the art to make and use the same, reference being had to the accompanying drawings, forming part of this specification, in which—

Figure 1 represents a front view of my improved copy-holder.

Figures 2 and 3 are similar views, showing modifications in its construction.

Figure 4 is a side view of the same.

Figures 5 and 6 are similar side views, showing modifications in its construction.

Figure 7 is a vertical cross-section of the same, the plane of section being indicated by the line *z z*, fig. 6.

Similar letters of reference indicate corresponding parts.

This invention relates to a new device for holding the manuscript on printers type-cases; and consists in the arrangement and construction of a platform, which rests on suitable supports provided for that purpose on the type-case, and which can be easily moved laterally on the said type-case, to enable the compositor to reach all the types. It is provided with a folding presser which has wire fingers for holding the manuscript on the platform, and is furthermore provided with a sliding indicator-bar, which is to show at a glance what line of the manuscript the compositor is copying. The platform is furthermore provided with sliding extensions, by which it is enabled to hold broad sheets of manuscript, said extensions being so arranged as to be easily brought out of the way when not required.

The object of the invention is to provide a manuscript-holder which is to supersede the weighted cord generally used, and by means of which the manuscript can be kept clean, and which holds the latter in such a way that it cannot be blown away nor disturbed by the wind, and which, furthermore, is adapted for all sizes of paper, from the smallest slip to the largest slip.

A represents a board made of wood or other suitable material. Its size would, by preference, be about like that of a sheet of ordinary foolscap paper, but it may, if desired, be made of any suitable dimensions. It is placed upon the type-case B, so as to rest upon a ledge, *a*, which is formed on the lower edge of the latter, as shown in figs. 1, 2, 4, and 5; and small rollers may be fixed on the ledge or on the board to facilitate lateral motion. At its upper end is an arm, *b*, which has at its end a roller, *c*, which rests upon the upper longitudinal lining *d* of the case B, as is clearly shown in figs. 1 and 4. By this arrangement the board A can be moved laterally on the case B to uncover types which may be needed for the composition. An equivalent for the arm *b* and roller *c* would be wire extension *e*, the two ends of which are fitted into the upper edge of the board A, while its outer bent end *f* rests upon the lining *d* of the case B, as is clearly shown in figs. 2 and 5. The lateral motion of the board on the case would be as easy as when the roller is used, especially if the part *f* of the wire *e* is rounded and bent downwards, as shown. Full equivalents for the extensions *e* and *b*, whereby also the ledge *a* could be dispensed with, would be two or more wires or rails, *g*, which are stretched across the case B, and which fit into grooves *h h*, which are provided for that purpose on the under side of the board A, as is clearly shown in figs. 3, 6, and 7. By this latter arrangement the board A would rest and easily slide upon the wires *g g*, and any further supports or guides would be unnecessary. Near to one side of the board A is arranged a bar, C, which is about as long as the board A. It is connected, by means of two or more spiral or other springs, *i i*, fig. 7, with the board A, said springs holding the bar C close to the board. A number of wire fingers, *j j*, for holding the manuscript upon the board, projects from one side of the strip C, and rest close upon the board A, as shown. The strip C is provided with a knob or handle, *k*, by which it can be turned so as to raise the fingers *j* from the board, and thus allow the insertion or removal of the manuscript. By attaching the ends of the springs *i* to the strip C and board A, hinges for connecting the said strip with the board are dispensed with; but, if desired, the strip C may be hinged to the board, and be acted upon by the spring *i* in such a manner that the fingers *j* will be pressed upon the board. D is a bar made of wood or sheet metal, and provided at its under side, at or near one end, with a tenon, *l*, which fits into a dove-tail or other groove, *m*, that is formed either directly in the face of the board, near one edge of the same, or on a strip, *n*, secured

thereto, said groove extending from top to bottom end of the board. The bar D is for the purpose of indicating the line for which the copy is being taken, and so to avoid the tedious searching for the required line. By the use of this bar type can be set much quicker than ordinarily. E E are two slotted sheet-metal plates, which are secured, by means of screws or pins, o, that fit through their slots, to the face of the board A, near to that edge of the same which is opposite to that near which the groove *m* and strip C are arranged. The object of these strips E is to allow an extension of the board, so that broader sheets of paper can be held thereon. They can also be used for holding small slips of paper, which are inserted under their inner ends by slightly raising the said end. F is a wire extension, which may, in place of or besides the plates E, be arranged on the board A. Its shape is fully shown in figs. 2, 3, and 7. It is so fitted in the holes which are bored into the edge of the board that it can be moved in or out at pleasure. An equivalent for the grooves *g* would be the use of staples or hooks, fitted to the under side of the board A so as to surround either partly or wholly the wires or rails *h*.

Having thus described my invention, what I claim as new, and desire to secure by Letters Patent, is—

1. The board A, when provided with the extension *b* and roller *c*, or their equivalents, and with the spring finger-bar C for holding the manuscript, substantially as and for the purpose herein shown and described.
2. The board A, when provided with the extension *e*, or its equivalents, and with the indicating sliding bar D, substantially as and for the purpose herein shown and described.
3. The board A, when provided with grooves *h h* or their equivalents, and with slotted plate or plates E or their equivalents, substantially as herein shown and described.
4. The board A, when arranged as described, so that it can be moved laterally on the type-case B, and when provided with the spring finger-bar C, sliding indicator-bar D, and extension-bars E, or equivalents, all made and operating substantially as and for the purpose herein shown and described.

P. A. LA FRANCE.
